UNITED STATES PATENT OFFICE.

SOLOMON MAAS, OF NEW YORK, N. Y.

PUZZLE.

SPECIFICATION forming part of Letters Patent No. 781,438, dated January 31, 1905.

Application filed June 6, 1904. Serial No. 211,300.

To all whom it may concern:

Be it known that I, SOLOMON MAAS, a citizen of the United States, and a resident of the borough of the Bronx, city of New York, county 5 and State of New York, have invented new and useful Improvements in Puzzles, of which the following is such a full, clear, and exact description as will enable any one skilled in the art to which it appertains to make and use the 10 same, reference being had to the accompanying drawings, forming part of this specification:

My invention relates to the class of puzzles in which a set of balls or rolling members are 15 rolled from certain starting point or points over circuitous paths to a certain objective point or points, with certain traps or hazards or obstructions arranged along the paths to increase the difficulty of getting the balls to 20 the objective point, the described features being arranged upon a suitable tray or platform which is designed to be held in the hand while being manipulated in the endeavor to solve the problem presented by the puzzle. The 25 present invention refers to this general class of puzzles in which the novel idea is used of having two different sets of balls or rolling members which are started from different points and are to be rolled over routes which 30 differ in parts and are common in other parts to a certain objective point or points.

Another feature of the invention is that of the scene of the Russian-Japanese war which is being carried on at the present date, and 35 particularly at the famous point, Port Arthur, China, and the circuitous paths or routes which the puzzle members may be rolled over on this scene are beset with such instruments of war as submarine mines, sunken obstructions 40 in the harbor, various forts in which the members are trapped unless much skill is used in rolling them by such point.

The invention seeks to provide a comparatively difficult and amusing puzzle embodying the above-stated features; and to these ends it consists in the various novel arrangements and combinations of the several different parts, all as hereinafter described and then pointed out in the claim.

I have illustrated a type of my invention in 50 the accompanying drawings, wherein—

Figure 1 is a plan view of the improved puzzle. Fig. 2 is a view in vertical section of a portion of the puzzle, the plan of which section is indicated by line 2 2, Fig. 1. 55

Referring to the drawings, in which like numbers of reference designate like parts throughout, 1 is a four-sided tray rectangular in shape, upon the interior of the bottom of which is arranged sections or areas 2, 3^a, and 3^b on the general order of a geographical map, the former section, 2, of which indicates the Peninsula of Liao Tung, China, while the latter, 3^a and 3^b, represents the surrounding water of the Gulf of Pe-chi-li and 65 the Yellow Sea. The marine section is divided into two parts 3^a and 3^b by means of a sunken obstruction 4, which is a partition and is supposed to indicate a so-called "sunken" vessel or suitable craft for blocking a channel, 70 and from this point on to the land extends a partition 5, and these two parts 4 and 5 divide the marine sections, so that the balls 6 in the former cannot get into the other section, in which are another set of balls, 7, the two sets 75 of balls being distinguished from each other in sets by any suitable sort of marking or coloring, they being here shown as distinguished by the set 6 being light in color and the set 7 being dark. The part 4 is in plan shaped 80 like a marine vessel and stands up from the bottom of the tray and together with the part 5 forms a continuous wall or division between the marine sections 3^a and 3^b, so that the set of balls in one section cannot pass to the other 85 and are thereby kept independent of each other. The balls 6 in the marine section 3 are to be rolled around a circuitous path provided by the upright partitions 8, 9, 10, and 11 in the effort to get them in the point marked 90 "Harbor" at Port Arthur, and these balls 6, being the marine ones, have the harbor at that point as their objective point, the idea being that the city is then taken by these members when they are rolled to that point. The 95 marine section extends entirely around the end of the peninsula and up alongside thereof, where it is guarded by the irregular-shaped

partition 12, and in the marine sections 3 and 3^a are arranged what may be termed "submarine mines" 13 and 14, respectively, and which consist in depressions in which the ball may fall if 5 not skilfully rolled around the same to avoid it, and this impedes the progress of the balls to that extent. The marine section 3^a, in which the so-called "land" or "infantry" members 7 are started, is guarded by suitable partitions 15, 16, and 17, there being an opening 10 between 15 and 16 at the point 18, through which the balls may be readily rolled and thence be supposed to be landed on the shore at 19, from which point they are to be rolled 15 along a circuitous path provided by a number of partitions, such as 20, 21, 22, 23, 24, 25, 26, 27, and 28, the objective point in this case being that of the point marked "City" in the loop-like partition 30. On the land-section 2 20 there are provided at different points suitable traps, indicated by the word "Fort" at 29, and in which the ball may get caught or lodged to impede its progress. The so-called "forts" 29 are made of thicker and more substantial 25 pieces than the partitions and are formed with recesses or cavities leading off from the pathway of the balls formed by partitions and are of such size as to permit a ball to lodge therein unless care be used to 30 make the ball escape such cavity. The partition 17 at one side provides a deep pocket 17^a, in which a ball after being landed may be trapped unless much care is used, and other arrangements of the partitions may be made to 35 increase the difficulties of a player operating the puzzle by tilting the board in a well-known manner to roll one set of the balls into the harbor and the other into the city as the objective points. The so-called "marine" and "land" 40 members 6 and 7, respectively, may have, if preferred, parts of the routes to the objective points in common on the land-section 2 by reason of an opening at 31, where the balls 6 may roll through onto the land-section and may 45 then take the land route by any of the several passages formed by the partitions and may all reach the objective point marked "City," formed by the looped partition 30. While the balls 6 are shown as located below the point 50 of the peninsula as the starting-point, they may be started higher up at the side at the left in Fig. 1, while the balls 7 may be started from the point indicated in said figure, thus increasing the difficulty of rolling the balls to 55 the objective points, since in this case they start from points at opposite ends of the board or tray 1. While I have indicated several of the well-known points of interest on this peninsula—such as Dalny, Nan-Shan Hill, Niu- 60 Chwang, as well as the famous Manchurian railroad—other features true to the geography

of this particular locality may be added in order to lend additional interest to the puzzle as an amusing device. The interior of the bottom of the tray is of course a flat surface 65 for the balls to be readily rolled over by the user holding the tray in his hand and tilting it out of the horizontal in various angles to guide the balls over certain routes. The geographical features of this section of the country are illustrated in the form of an ordinary map, which may be variously colored, and the various partitions may be made of wood or paper or other suitable material that is generally used in this class of puzzle. 75

Having thus described my invention, what I claim, and desire to secure by Letters Patent, is—

A puzzle comprising a suitable tray having arranged upon the bottom thereof a representation of a certain geographical locality including a fortified point of land and the surrounding waters with a harbor for the said fortified point, an objective point located on the fortified land-section and another objective 80 point located in the harbor of said water-section, a series of circuitous passages located upon the land-section and through which balls may be rolled to the objective point on the fortified land-section, a suitable obstruction 85 or wall dividing the said water-section into two independent parts and one of said parts being provided with passage-ways leading to the said harbor and the other said independent water part being provided with passage- 90 ways leading to said land-section thence via said circuitous passages to said fortified point on the land, two differently-marked and distinct sets of balls one set starting from one 95 part of said water-section and destined for the 100 said harbor objective point and the other starting from the other part of said water-section and destined for said fortified objective point on the land via the land-section, the said 105 obstruction or dividing-wall of said water-section 110 serving to prevent one set of balls from passing from its water-section into the other except by way of the land-section, the coastline of said land-section having an obstruction or wall extending along the same so as to divide the land from the water, the said 115 passages leading from said water part to the land extending through said coast wall or part, substantially as and for the purpose set forth.

In testimony whereof I have hereunto set 115 my hand in the presence of the two subscribing witnesses.

SOLOMON MAAS.
